DESIGN FOR AN UMBRELLA

Charles M. Preaus, Tulsa, Okla., assignor of one-half to Charles E. Ross, Tulsa, Okla.

Application January 9, 1947, Serial No. 136,026

Term of patent 14 years

(Cl. D88—3)

To all whom it may concern:

Be it known that I, Charles M. Preaus, a citizen of the United States, residing at Tulsa, in the county of Tulsa and State of Oklahoma, have invented a new, original, and ornamental Design for Umbrellas, of which the following is a specification, reference being had to the accompanying drawing, forming part thereof.

Fig. 1 is a top plan view of an umbrella, showing my new design.

Fig. 2 is a side elevation of the same.

I claim:

The ornamental design for an umbrella, as shown.

CHARLES M. PREAUS.
